WATER TUBE CONNECTION

Filed July 15, 1926

INVENTOR:
Russell H. Wilhelm
BY *Herbert G. Ogle*
HIS ATTORNEY

Patented July 2, 1929.

UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

WATER-TUBE CONNECTION.

Application filed July 15, 1926. Serial No. 122,638.

This invention relates to rock drills, but more particularly to a water tube connection for that type of rock drills in which water is supplied to a hollow drill steel for cleansing the drill hole.

The objects of this invention are to seal the water tube in the back head so as to prevent water from being forced into the cylinder, to protect the water tube against injury by the securing means and to prevent improper assembly of the parts comprising the connection.

Other objects will be in part obvious and in part pointed out hereinafter.

The invention consists of the combination of elements and arrangement of parts substantially as hereinafter described and more particularly pointed out in the appended claims and illustrated in the accompanying drawings, in which

Figure 1 is an elevation of a rock drill partly in section illustrating an embodiment of the invention, and

Figure 2 is an enlarged detail sectional elevation of the back head and the water tube parts.

Referring to the drawings, A represents a rock drill cylinder in which is arranged a reciprocating piston B, only the front end of which is shown. A back head C forms a closure for the rearward end of the cylinder A. A front cylinder extension D forms a closure for the front end of the cylinder and supports at its front end a front head E. Within the front cylinder extension D and the front head E is a chuck F, the front end of which is provided with internal screw threads G to receive a correspondingly threaded chuck jaw H. In this instance the chuck jaw H is provided with diametrically opposed longitudinal slots J, the sides of which cooperate with wings K of a drill steel L extending into the front head for preventing relative rotation between the drill steel and the chuck jaw H.

Interposed slidably in the chuck F and between the piston B and the drill steel L is an anvil block O for transmitting the blows of the piston to the drill steel. Seated on the cylinder A is a valve chest P in which is disposed a suitable distributing valve (not shown) for controlling the admission of pressure fluid to the cylinder to actuate the piston B. Such pressure fluid may be conveyed from a suitable source of supply by a connection

Q secured to the valve chest and the admission of pressure fluid to the valve chest may be controlled by a suitable throttle valve (not shown), the controlling lever of which is designated by R.

In certain types of rock drills such as that illustrated in the drawing, provision is usually made for conveying cleansing liquid from the back head through the cylinder and the reciprocating parts into the hollow drill steel L for cleansing the drill hole. Accordingly, in the present instance, a longitudinal recess S is formed in the back head C and a smaller bore T is formed in the back head coaxially with the recess S to receive a water tube U having a reduced forward end V which extends into the hollow bore of the drill steel L. A flat end wall W of the recess S forms a seat for a bulb X formed near the rearward end of the water tube U and also for a packing member Y, preferably of rubber, which encircles the end of the tube U and closely fits the walls of the recess S.

Disposed slidably in the recess S is a bushing Z having a central bore b to receive the end of the water tube U. The bushing Z is seated on the packing member Y and has an annular groove c which communicates with the bore b through radial passages d for conveying water to the tube, such water in the present instance being supplied to the recess S by a connection e leading from a source of supply and through a passage f in the back head communicating with the annular groove c.

Seated on the rearward end of the bushing Z is a packing member g for preventing leakage of water through the outer end of the recess S. This packing member g is preferably of the same size and form as the packing member Y and is provided with a central aperture h through which extends a forward extension i of a compression plug k. The extension i of the compression plug k is preferably substantially of the same diameter as the water plug U and is of a length to permit the end thereof to extend slidably into the bore of the bushing Z. A flange o of the compression plug k is adapted to fit slidably the recess S and is seated on the rearward end of the packing member g, thus preventing rotation of said packing member with a water plug p screwed into a threaded portion q of the recess S for compressing the packing members Y and g. In the present instance a

rearward extension *r* of the compression plug *k* extends slidably into a recess *s* of the water plug *p* to centralize the compression plug *k* in the recess *S*.

5 The threaded portion of the water plug *p* is preferably of such length that a considerable portion thereof extends rearwardly of the back head *C* to enable a lock nut *t* to be screwed thereon for locking the water plug 10 securely in position.

By means of the foregoing described invention, leakage of water from the recess *S* into the cylinder *A* and from the rearward end of said recess is entirely eliminated. The parts comprising the connection are few in number, they are of simple and inexpensive construction, the packing members *Y* and *g* and the bushing *Z* are reversible so that little 15 attention is required as to their proper position in the recess *S* when these parts are assembled in the back head.

I claim:

1. In a rock drill, the combination of a cylinder, a back head for the cylinder having a recess, a water tube in the cylinder extending into the recess, a packing member in the end of the recess encircling the water tube to prevent leakage of water into the cylinder, means slidable in the recess to receive the end of the water tube and to convey water to said tube, a packing member seated on said means for preventing leakage of

water from the recess, a water plug for compressing the packings and holding the water tube against endwise movement, and a compression plug between the last said packing member and the water plug forming a seating surface for the water plug. 35

2. In a rock drill, the combination of a cylinder, a back head for the cylinder, a threaded recess in the back head having a flat end wall, a water tube in the cylinder extending with one end into the recess, a bulb on the tube seating on the end wall, a packing member abutting the end wall and encircling the water tube to prevent leakage of water into the cylinder, a bushing slidable in the recess to receive the end of the water tube, said bushing having passages for conveying water to the tube, a packing member seated on the bushing to prevent leakage of water from the recess, a water plug screwed into the recess for compressing the packing members, a compression plug extending into the last said packing member and into the water plug, and a flange on the compression plug interposed between the last said packing and the water plug to prevent the transmission of the rotary movement of the water plug to the packing during the threading of the water plug into the recess. 40 45 50 55 60

In testimony whereof I have signed this specification.

RUSSELL H. WILHELM.
